TIE PLATE.

1,426,312.

Specification of Letters Patent. Patented Aug. 15, 1922.

Application filed November 29, 1921. Serial No. 518,499.

To all whom it may concern:

Be it known that I, ANDREW MORRISON, a citizen of the United States, residing at Penn Township, in the county of Allegheny and State of Pennsylvania, have invented a new and useful Improvement in Tie Plates, of which the following is a full, clear, and exact description.

The present invention relates particularly to tie plates for railroads.

An object of the present invention is to provide a tie plate in which all of the bearing surfaces, including the rail tread and the upper surface of the tie plate, are normal to the downward thrust produced by the wheel load, and in which the lower surface of the plate is shaped to afford a maximum resistance to lateral outward movement thereof, by providing upwardly and outwardly inclined shoulders forming abutments acting in opposition to such movement and by the addition to the under surface of supplemental ribs, the resistance of which cooperates with the resistance afforded by said inclined shoulders.

The foregoing and other objects of the present invention, together with their attendant advantages, will be apparent as the invention becomes better understood by reference to the accompanying specification and drawings forming a part thereof, it being premised that changes may be made in the details of construction and manner of operation without departing from the spirit of my invention or the scope of my broader claims.

Figure 1 is a transverse section through a tie plate and rail showing a portion of a standard coned tread car wheel;

Figure 2 is a perspective view of the improved tie plate; and

Figure 3 is a diagrammatic illustration of the influences with special reference to which the present tie plate is designed.

The present invention relates generally to tie plates of the type disclosed and claimed in my Patent No. 1,348,370 of August 3rd, 1920, and embodies several of the features of the patented structure.

It is designed, however, to provide a tie

plate in which additional resistance to the spreading tendency is afforded.

The general problems involved in tie plate constructions, and successfully overcome by the present invention, have been recognized and unsuccessful attempts have been made to overcome the same by constructing a cambered tie plate having an upper rail seat normal to the line of thrust of the standard coned tread car wheel and lower stepped surfaces parallel with said seat. Such tie plates have been constructed both with and without supplemental protuberant ribs, but stepped surfaces arranged in this manner parallel with the rail seat have tended to assist rather than prevent the lateral spreading tendency.

Referring more particularly to the drawings, there is illustrated a tie plate 2 provided with a rail abutting shoulder 3 adjacent one end thereof and with the usual spike openings 4 to assist in holding the tie plate in position. According to the present invention, the main body of the tie plate, which is preferably not cambered, is slightly tapered to provide a thickened portion adjacent the shoulder 3 and a relatively thin inwardly projecting portion. The taper is calculated in such manner that the upper rail seat 5 will be substantially normal to the downward thrust of a standard coned tread car wheel, such as illustrated in dotted lines in Figure 1. Such a car wheel produces a wheel load stress in the direction of the inclined line *a*—*b* of Figure 1, while the wheel load is effective in a vertical direction. In Figure 3 this load is indicated by the arrow *A* designated "wheel load." In addition to the wheel load stress there is a laterally acting stress indicated in Figure 3 by the arrow *B*, designated "wheel thrust." These two stresses, which are continuously acting during the passage of a car over the rails, produce a third stress indicated in Figure 3 by the arrow *C*, designated "resultant wheel thrust." It will be apparent that all of these stresses combine to produce a "spread" of the rails, and the tie plates as represented by the arrow *D*.

The present invention partially overcomes this spreading tendency by forming the lower surface of the tie plate of a series of wide bearing surfaces 6, which are oppositely inclined with respect to the upper rail seat, the inclination of these bearing surfaces being upwardly and inwardly. At the high points of each of the bearing surfaces there are provided means, in the form of projecting ribs 7, which assist in overcoming the spreading tendency. The bearing surfaces 6, and the inclined portions 8, are of no value so far as offering any resistance to spread in the direction indicated by the arrow D. The opposite side of the ribs, however, presents an abrupt upwardly and outwardly inclined shoulder which connects the highest point of the ribs with the lowest point of the adjacent surfaces 6. This provides a much more effective abutment than is provided with a construction such as illustrated in my prior Patent No. 1,348,370. In Figure 3 the arrows E, which are designated "resistance by inclined portions" indicate the resistance which would be provided if the ribs 7 were not projected from the surfaces 6, or, in other words, indicate the resistance of that portion of the shoulder above the rib, and the arrow F designated "supplemental resistance by ribs," indicates the additional resistance which is provided by reason of these ribs. It is essential that the effective portions be abrupt, as a gradual inclination would tend to assist the "resultant wheel thrust" and increase the lateral outward creeping of the tie plates, thereby permitting an undue spreading action.

With a construction of the present nature, the greatest depth of the abrupt inclined portions is effective in direct opposition to the "resultant wheel thrust," thereby preventing any spreading or breaking.

The advantages of the present invention arise from a tie plate provided with an upper bearing surface substantially normal to the downward line of stress of a standard coned tread car wheel, and having an under surface in which the maximum resistance is directly effective for maintaining the tie plate in fixed position on the tie.

I claim:

1. A tie plate for railway rails, having an upper rail seat substantially normal to the line of thrust of a standard coned tread car wheel and having a series of wide lower bearing surfaces upwardly and inwardly inclined at an oblique angle to the rail seat, said upwardly inclined surfaces being connected by projecting ribs, substantially as described.

2. A tie plate for railway rails, having an upper rail seat substantially normal to the line of thrust of a standard coned tread car wheel and having a series of wide lower bearing surfaces upwardly and inwardly in-

clined at an oblique angle to the rail seat, said upwardly inclined surfaces being connected by projecting ribs so disposed that their maximum resistance is effective to prevent outward spreading tendency of the tie plate, substantially as described.

3. A tie plate for railway rails, having an inclined upper rail seat substantially normal to the line of thrust of a standard coned tread car wheel and a lower tie-engaging surface comprising a series of wide bearing surfaces oppositely inclined with respect to said seat, the inclination of said surfaces being gradually upwardly and inwardly, and ribs at the high points of said bearing surfaces, substantially as described.

4. A tie plate for railway rails, having an inclined upper rail seat substantially normal to the line of thrust of a standard coned tread car wheel and a lower tie-engaging surface comprising a series of wide bearing surfaces oppositely inclined with respect to said seat, the inclination of said surfaces being gradually upwardly and inwardly, and ribs at the high points of said bearing surfaces, said ribs presenting a greater surface on one side than the other, the surface of greater width being inclined abruptly upwardly and outwardly to prevent spreading of the tie plate, substantially as described.

5. A tie plate for railway rails having an inclined upper rail seat, and a lower tie-engaging surface comprising a series of wide bearing surfaces across substantially the entire width thereof and oppositely inclined with respect to said seat, said inclination being gradually upwardly and inwardly, abruptly upwardly and outwardly inclined portions forming shoulders resisting spreading tendency of the tie plate, and ribs adapted to supplement the action of said upwardly and outwardly inclined portions, substantially as described.

6. A tie plate for railway rails having an inclined upper rail seat, and a lower tie-engaging surface comprising a series of wide bearing surfaces across substantially the entire width thereof and oppositely inclined with respect to said seat, said inclination being gradually upwardly and inwardly, abruptly upwardly and outwardly inclined portions forming shoulders resisting spreading tendency of the tie plate, and means projecting beyond the high points of said wide bearing surfaces and adapted to supplement the action of said upwardly and outwardly inclined portions, substantially as described.

7. A tie plate for railway rails having a downwardly and inwardly inclined upper rail seat, and a lower tie-engaging surface comprising a series of spaced broad bearing surfaces extending gradually upwardly and inwardly to provide a tapered tie plate construction in which all of the lowered broad tie-engaging surfaces extend angularly with

respect to the rail seat, said broad surfaces extending across substantially the entire width of the tie plate and shoulders extending transversely of said plate and connecting adjacent portions of said surfaces, said shoulders being effective for partially counter-acting the tendency of the plate to spread outwardly, and ribs extending transversely

of the plate adjacent the high points of the tie-engaging portions of the plate for supplementing the action of said shoulders, substantially as described.

In testimony whereof I have hereunto set my hand.

ANDREW MORRISON.
